UNITED STATES PATENT OFFICE.

RUSSELL I. WILCOX, OF CHICAGO, ILLINOIS, ASSIGNOR, BY MESNE ASSIGNMENTS, TO
WESTERN ELECTRIC PIANO COMPANY, OF CHICAGO, ILLINOIS, A CORPORATION OF
ILLINOIS.

AUTOMATIC PLAYER PIANO.

Application filed July 5, 1923. Serial No. 649,395.

To all whom it may concern:

Be it known that I, RUSSELL I. Wilcox, a citizen of the United States, and resident of Chicago, in the county of Cook and State 5 of Illinois, have invented a certain new and useful Improvement in Automatic Player Pianos, of which the following is a full, clear, concise, and exact description, reference being had to the accompanying 10 drawings, forming a part of this specification.

This invention relates to automatic player pianos of the character in which an indicator may be set to determine the particular 15 selection from a number of selections on a single music sheet which is to be played. Then upon the insertion of a coin, or upon otherwise tripping the mechanism, the music sheet is rapidly wound in one direction or the other as required to automatically 20 select the desired piece, and then is wound slowly forward to play the selected piece.

The object of the invention is to provide 25 a device of this character which will be simple in construction and easy and certain in operation, and in which the probability of the selecting mechanism getting out of adjustment is reduced to a minimum.

Another object of the invention is to provide 30 a new and improved expression device which will operate to more perfectly control the volume of sound of the instrument.

One of the features of the invention is 35 the selection controlling mechanism in which the co-operating valve members are both driven, an arm being set to automatically shift one of said valve members in relation to the other to effect the selection of 40 the desired piece.

Another feature resides in the expression device which is so constructed as to obtain practically any degree of volume between the two extremes of loud and soft.

Other features and advantages will appear 45 from time to time as the description of the invention progresses.

In the drawings—

Figure 1 is a face view of the tracker 50 board of the player with the principal parts of the controlling mechanism associated therewith;

Figure 2 is a section on the line 2—2 of Figure 1;

Figure 3 is a section on the line 3—3 of 55 Figure 1;

Figure 4 is a section on the line 4—4 of 60 Figure 3;

Figure 5 is a sectional view through the selecting mechanism with parts broken 65 away to show the driven selecting member and the relation of the distributing disc thereto;

Figure 6 is a detached perspective view 70 of one of the selecting valve elements;

Figure 7 is a section on the line 7—7 of 75 Figure 1, and shows the tilting bar which, upon actuation, is arranged to move the clutch members of the device into slow, forward or playing position;

Figure 8 is a section on the line 8—8 of 80 Figure 3;

Figure 9 is a sectional view through the cut-out valve;

Figure 10 is a cross sectional view through 85 the valve shown in Figure 9;

Figure 11 is a sectional view through one of the drive clutches of the selecting mechanism;

Figure 12 is a side elevation of the expression 90 controlling bellows;

Figure 13 is a section on the line 13—13 of Figure 12;

Figure 14 is a section on the line 14—14 of Figure 13;

Figure 15 is a view of the lower portion 95 of the expression device substantially on the line 15—15 of Figure 13;

Figure 16 is a diagrammatic layout showing the pneumatic connections between the several parts of the controlling mechanism, and

Figure 17 is a section on the line 17—17 of Figure 1.

It is believed the invention will be best 100 understood by a detailed description thereof taken in connection with the accompanying drawings.

Referring now to the drawings, in which like reference characters indicate like parts 105 in the several figures, 20 indicates the drive shaft which may be driven from an electric motor, or other suitable source of power. The main drive shaft 20 is joined to the operating shaft 21 through the medium of a clutch member consisting of the sliding sleeve 22 which is secured on the end of the shaft 20 by means of the pins 23 pass-

ing through slots 24 in the sleeve 22. Sleeve 22 is normally forced toward the left by means of the compression spring 25, and is provided at its left end with the notches 26 which receive the pins 27 extending from the opposite sides of the shaft 21.

Fixed to the shaft 21, in any desired manner, is the gear 28 and the relatively small gear 29. The gear 29 may, if desired, be formed by cutting the teeth directly into the shaft 21. Mounted substantially in a plane with the shaft 21 are the shafts 30, 31 and 32. The shafts 30 and 32 are arranged in axial alignment with the music sheet drum shafts 33 and 34 respectively, and may be merely extensions thereof.

Loosely mounted on the shaft 30 is the gear 35 which meshes with the gear 28, and the gear 36 which meshes with the gear 29. Loosely mounted on the shaft 32 is the gear 37 which meshes with the idler gear 38 mounted on the shaft 31, which in turn meshes with the gear 28. The idler gear 38 is provided between the gear 28 and the gear 37 in order that the shaft 34 may be driven in the opposite direction from the shaft 33.

Fixed to the shaft 30, in any desired manner, are the sleeves 39 and 40. Slidably mounted on the shaft 30 is the collar 41. The collar 41 is provided with the oppositely extending fingers 42 and 43 which slidably pass through notches 44 and 45 respectively in the sleeves 39 and 40 respectively. When the collar 41 is shifted to the right, as seen in Figure 1, the end of the pin 42 will be brought into the path of a lug 46 fixed to the hub 47 of the gear 35. Thus, as the gear 35 is in mesh with the driven gear 28, and as the pin 42 slidably passes through the notch 44 in the collar 39, which is fixed to the shaft 30, the shafts 30 and 33 will be driven whenever the clutch sleeve 40 is in its right hand position.

Slidably mounted on the shaft 32 is a collar 48 provided with a finger 49 which passes freely through a notch 50 in the sleeve 51 fixed to the shaft 32. When the collar 48 is shifted to the right, as seen in Figure 1, the end of the finger 49 is brought into the path of the lug 52 carried by the hub 53 of the gear 37. Thus, as the gear 37 is driven from the gear 28 through the medium of the idler gear 38, the shaft 32 and its extension 34 will be driven.

Pivottally mounted on the screw or bolt 54 carried by the bracket member 55 is a bar 56. The bar 56 is provided with the laterally extending pins 57 and 58 which engage the grooves 59 and 60 in the collars 41 and 48 respectively. Thus it will be noted that when the lower end of the bar 56 is moved to the right, pin 42 will be in a position to be engaged by the lug 46, thus causing the shaft 33 to be driven. If, however,

the lower end of the bar 56 is moved to its left hand position, indicated by the dotted lines, the pin 49 carried by the collar 48 will be positioned in the path of the lug 52, and the extension shaft 34 will be driven. When, however, the bar 56 occupies a mid position, as indicated in full lines in Figure 1, the downwardly extending end 61 of the finger 43 will be placed in the path of one of the lugs 62. The shaft 33 will now be driven through the medium of the gears 29 and 36. The gears 29 and 36 are so proportioned that gear 36 will make approximately one revolution to twenty revolutions of the gear 29. The gears 28, 35 and 37 are all of substantially equal size. Thus when the shafts 33 or 34 are driven through the medium of the gears 35 or 37, they will move approximately twenty times as fast as will the shaft 33 when driven through the medium of the gears 29 and 36.

Gears 35 or 37 will be clutched to their respective shafts to wind the music strip rapidly forward or backward to select a desired piece on the strip, while gear 36 will be clutched to shaft 30 to wind the music strip slowly forward to play the selected piece.

Carried on the shafts 33 and 34 are the music sheet drums 63 and 64 respectively. When the bar 56 is moved with its lower end to the left (Figure 1), the gear 37 will be fixed to the shaft 32, and the drum 64 will be rotated rapidly to rewind the music sheet. If, however, the lower end of the bar 56 is moved to its right hand position, gear 35 will be fixed to the shaft 30 and the drum 63 will be rotated rapidly to wind the music sheet forward. If, however, the bar 56 occupies an intermediate position, the gear 36 will be fixed to the shaft 30 and the drum 63 will be rotated to slowly wind the music sheet forward to play the selected piece. Rotating with the music sheet rolls 63 and 64 are music roll drags 63' and 64' in the form of small grooved rollers on the shafts 33 and 34. Friction drag means engage with each of these rollers, such drag means not being illustrated as they are elements well known in the art.

Loosely secured to the lower end of the bar 56 is a rod or link 65 which is adapted to be acted on by the rewind pneumatic 66 or the fast forward pneumatic 67 to shift the bar 56 into either of its extreme positions. The pneumatic 66 is provided with a projection 68 adapted to engage the lug 69 on the rod 65 when the pneumatic is collapsed, and, in like manner, the pneumatic 67 is provided with a projection 70 adapted to engage the lug 71 on the rod 65 when this pneumatic is collapsed. Thus, when the rewind pneumatic 66 is collapsed, the lower end of the bar 56 is moved to the left and will cause the drum 64 to be rotated rapidly.

to rewind the music sheet. If, however, the fast forward pneumatic 67 is collapsed, the bar 56 will be moved to its extreme alternate position, and the drum 63 will be rotated 5 to rapidly wind the music sheet forwardly.

The mechanism for moving the bar 56 into its intermediate or playing position will now be described. Rotatably mounted, by means of the pivots 72 which pass loosely 10 through openings in the bracket members 73, is a bar 74. The bar 74 is provided with a pair of fingers 75 and 76 which extend adjacent to the bar 56 on opposite sides of its pivotal support 54. Extending laterally 15 from the bar 74 adjacent to the lower end thereof is an arm 77 connected by a link 78 to the movable part of the slow forward or playing pneumatic 79. Thus when the pneumatic 79 is collapsed, the bar 74 is 20 moved about its pivots 72 to bring the laterally extending fingers 75 and 76 into engagement with the edge of the shift bar 56, insuring that the bar 56 will be moved to its intermediate or playing position.

25 From an inspection of Figure 1, it will be noted that when the bar 56 occupies an intermediate position, the fingers 42 and 49 are disengaged from the lugs 46 and 52 respectively, so that the shaft 33 is now driven 30 through the medium of gears 29 and 36. As the lugs 62 carried by the hub of the gear 36 are engaged only by the downwardly projecting portion 61 of the finger 43, it is evident that when the collar 41 is moved either 35 to its extreme right hand or left hand position, the gear 36 will freely rotate on the shaft 30.

Briefly stated, the clutch mechanism operates as follows: If the rewind pneumatic 66 40 is collapsed, the lower end of bar 56 is moved to its extreme left position, and gear 37 is locked to the shaft 32, gears 35 and 36 at this time being free to rotate about the shaft 30. If the fast forward pneumatic 45 67 is collapsed, the lower end of bar 56 is moved to its extreme right position, locking gear 35 to shaft 30, the gears 36 and 37 at this time being free on their respective shafts. If, however, the slow forward or 50 playing pneumatic 79 is collapsed, the bar 74 is rotated about its pivots 72, moving the bar 56 to its intermediate position, thus disconnecting the gears 35 and 37 from their respective shafts and locking gear 36 55 to the shaft 30.

When bar 56 has been shifted to either of its extreme positions, its movement back to its intermediate position is resisted by the following means. On the side of the bar 56 60 is rotatably secured the disc 256 which is engaged by the laterally extending portion 257 of the bar 258. The bar 258 is pivotally supported at 259, and the portion 257 thereof is forced toward the disc 256 by the action of tension spring 260.

The indicating and selecting mechanism will now be described, reference being had particularly to the left portion of Figure 1 and Figures 3, 4, 5, 6 and 17. Rotatably mounted on the shaft or spindle 80 (see Figure 3) is a worm wheel 81 which meshes with the worm 82 fixed to the shaft 83. Fixed to the shaft 83 is a star wheel 84 provided with four radially extending slots 84'. Frictionally secured to the portion 85 of 70 the supporting shaft for the forward wind drum 63, by sleeve 88, is an arm 86 provided at diametrically opposite points with the laterally extending pins 87 adapted to engage successively in the slots 84' upon rotation 75 of the shaft 85. Thus the wheel 81 will be rotated, step by step, upon rotation of the drum 63. The purpose of this will be presently explained.

As the shaft 85 rotates with the forward 85 wind drum 63, it will be obvious that through the arm 86, disc 84 and the worm 82, the worm wheel 81 will be driven in one direction or the other according to whether the music sheet is being wound on or un- 90 wound from the drum 63.

Snugly engaging the left side of the worm gear 81 is a distributing disc 91 which is provided with four concentric grooves 92, 93, 94 and 95 (see Figure 5). The disc 91 95 is held against rotation with the gear 81 but is slidably mounted on a sleeve 89 so that it may be resiliently pressed against the gear by the spring 90. The disc 91 is held against rotation by a fork 91^a which embraces a fixed rod or pin 91^b (Figures 4 and 5). A collar 89' on the sleeve 89 acts as a rear abutment for the spring 90. The worm gear 81 is provided with four openings 100 which extend therethrough. The outermost opening 96 extends directly through the wheel 81 and communicates with the outermost groove 92 in the distributing disc 91. The left opening 97 slants slightly upwardly, as seen in Figure 5, and communicates with the groove 93 in the distributing disc. The lowermost opening 98 slants downwardly and communicates with the innermost groove 95 in the disc 91 while the right hand opening 99 communicates with the groove 94. It may be here explained 105 that the sole purpose of the disc 91 is to provide constant communication between the openings 96, 97, 98 and 99 in the right face of the worm gear 81 and the tubes 100, 101, 102 and 103 which communicate with 110 the grooves 92 to 95 respectively.

Rotatably mounted on the right face of the worm gear 81, by means of the screw 104, is the disc 105. The screw 104 taps 125 into the gear 81, and a spring 104 under the head of the screw urges the disc 105 against the gear 81. The disc 105 is provided with a central concentric groove 106 (see Figure 6) and a laterally extend- 120

- ing slot 107 communicating therewith. The concentric groove 106 is adapted to overlie the opening 96 in the face of the worm gear 81. Thus the groove 106 and 5 its extension 107 are at all times connected to the tube 100 through the distributing disc 91. As above stated, the disc 105 is rotatably mounted on the face of the worm gear 81, and when rotated in a clockwise direction, as viewed from the right in Figure 3, the extension 107 is adapted to overlie and communicate with the opening 97 in the worm gear and be connected through the groove 93 in the distributing 10 disc 91 to the tube 101. When, however, the disc 105 is rotated in a counterclockwise direction, the extension 107 will overlie the opening 99, thus effecting communication through the groove 94 to the tube 102. 15 When the disc 105 occupies an intermediate position, the extension 107 will overlie the opening 98, thus effecting communication through the groove 95 to the tube 103. Briefly stated, the disc 105 acts to complete 20 communication from the tube 100 to the tubes 101, 102 or 103 according to whether the disc is rotated in a clockwise direction to its extreme position, in a counterclockwise direction to its extreme position, or is 25 left in intermediate position.
- Fixed to the shaft 80 for rotation therewith is an arm 108 provided with an inwardly extending finger 109 adapted to engage with the notch 110 in the circumference of the disc 105 to rotate the disc to its various operative positions. For illustration, if the shaft 80 is rotated in a clockwise direction, as viewed from the right in Figure 3, the disc 105 will also be rotated in a 30 clockwise direction until the finger 109 passes out of the notch 110. This operation will rotate the disc 105 just far enough so that the extension 107 will overlie the opening 97 in the face of the worm gear 81. If, 35 however, the shaft 80 is rotated in a counterclockwise direction, the finger 109 will operate to rotate the disc 105 in a similar direction to position the extension 107 over the opening 99.
- Carried at the outer end of the arm 108 is 40 a sleeve 112 within which is slidably arranged a plunger 113 provided at the inner end thereof with an anti-friction device, such as a roller 114. A compression spring 45 115 is positioned between a shoulder on the sleeve 112 and the head of the plunger 113, and normally operates to force the plunger toward the right, as seen in Figure 3.
- Pivotaly supported by the ears 116 on the 50 arm 108 is a lever 117, the lower end of which is adapted to engage the flange 118 of the collar 119 slidably mounted on the shaft 80. The flange 120 of the collar 119 is arranged to be engaged by the bifurcated 55 end of the strap 121 fixed to the movable

side of the pneumatic 122. The pneumatic 122 is connected through the tube 123 to the main bellows, (not shown) and, therefore, constantly tends to collapse whenever the instrument is in operation. The result of this 70 is that the lower end of the lever 117 is urged toward the right, thus forcing the plunger 113 towards the left and maintaining the roller 114 in engagement with the face of the worm gear 81. The worm gear 81 is provided with an opening 124 which is 75 in the path of travel of the roller 114, and is positioned on the radius of the worm gear 81 which passes through the opening 98 and pivot screw 104. Thus whenever the main 80 bellows of the instrument is in operation and the arm 108 reaches a position such that the extension 107 in the disc 105 overlies the opening 98, the roller 114 will be forced into the opening 124 in the worm gear and 85 lock the parts in this position.

It may be here noted that the opening 99 through the tube 102 controls the actuation of the rewind pneumatic 66, the opening 97 through the agency of tube 101 operates to 90 control the actuation of the fast forward pneumatic 67, and the opening 98 through the agency of tube 103 operates to control the actuation of the slow forward or playing pneumatic 79. The manner in which 95 this is brought about will be subsequently described.

The disc 105 is provided in its edge with a plurality of depressions 125, 126 and 127. Rotatably mounted on the pin 128 (Figure 4) is an arm 129 having an offset end 130 adapted to engage the notches 125, 126 and 127, and thus tend to retain the disc 105 in its actuated positions. The notches 125, 126 and 127 are arranged in accordance with the 100 positions which the disc 105 must occupy in order that the extension 107 may overlie the openings 97, 98 and 99 respectively. The extension 130 is maintained in engagement 105 with the periphery of the disc 105 by means 110 of the spring 131 which tends to rotate the cam in a clockwise direction, as seen in Figure 4.

Fixedly mounted about the shaft 80 is a dial 132 which is provided with divisions 115 about its circumference ranging from 0 to 100, as shown at the left in Figure 1. Fixed to the shaft 80 is a pointer 133 which is adapted to be moved over the dial 132 when the shaft 80 is rotated by means of the hand wheel 134. The right hand side of the dial is provided with an arcuate slot 135 in which is mounted an adjustable stop 136. By releasing the nut 136' the stop can be shifted 120 to any desired point in the slot and clamped there. This stop is intended to be set on the dial in a position corresponding to the end of the last selection on the sheet, which may be determined from a stop setting number 125 on the music sheet, or by trial. This 130

stop prevents the pointer 133 being advanced beyond this point.

It may be here briefly explained that when a new music sheet strip is placed on the rolls 5 63 and 64, the pointer 133 is placed at 0 at the beginning of the strip, and as the piece is wound forward from the drum 64 onto the drum 63, the indication of the pointer at the beginning of each of the successive 10 pieces or selections is noted. Thus, the hand 133 may point to 13 at the beginning of the second piece, 25 at the beginning of the third, 40 at the beginning of the fourth, and so forth. Then a program may be made 15 out in which the title of each of the selections will be followed by an indication as 13, 25, 40, etc., and in the subsequent operation of the instrument, the particular piece will be selected by moving the pointer to 20 the corresponding indication on the dial. As shown in Fig. 3, the dial may be mounted on a stationary boss 138 through the provision of a spring pressed detent 139 on the rear of the dial which is adapted to snap 25 into a small opening in the top of the boss 138.

In order that the shaft 80 may remain stationary after being set to indicate a selection, and yet may be readily moved to make 30 the selection, the following mechanism is provided. Fixed to the left end of the shaft 80, as seen in Figure 3, is a brake disc or drum 150 adapted to be engaged by a brake shoe 151 (Figures 1 and 3). The brake shoe 35 151 is carried by a lever 152 which is pivotally mounted on the stud 153. The movable side 154 of the pneumatic 155 is provided with an arm 156 which is adapted to engage the projecting end 157 of the brake lever 40 152. The pneumatic 155 is connected through the medium of the tube 158 directly to the main bellows (not shown). Thus when the player is at rest, the shaft 80 may be readily turned to indicate the selection 45 desired. When, however, the instrument has been started into operation, the pneumatic 155 will be collapsed, causing the brake shoe 151 to firmly engage the brake disc 150, thus tending to prevent rotation 50 of the shaft 80.

Projecting from the worm gear 81 is a lug 159 which, upon rotation in one direction, is adapted to engage the lug 160 adjacent to the worm 82 and upon rotation of the 55 worm gear in the opposite direction, the lug 159 will engage the lug 161 on the opposite side of the worm 82. This arrangement is provided in order to limit the degree of rotation of the worm gear 81. Should the 60 drum 64 continue to rotate after the lug 159 has engaged the lug 160, or lug 161, the shaft 85 will turn in the sleeve 88, thus preventing damage to the selecting mechanism.

65 The structure of the cut-out valve will

next be described. The purpose of this cut-out valve, shown in detail in Figures 9 and 10, is to in one position cut off the connection of the tube 103 to the valve chest and open the tube 102 directly to the atmosphere, and in the other position to close the opening in the tube 102 to the atmosphere and connect the tube 103 through to its particular operating part in the valve chest. This valve is operated in one direction when 70 the "rewind" cutting at the end of the music strip passes over the tracker bar, and in the other direction when the "replay" cutting in the music strip, preceding the first selection, passes over the tracker bar. When 80 the valve is actuated by the "rewind" cutting, the rewind pneumatic 66 is caused to collapse, and when actuated by the "replay" cutting at the beginning of the music strip, the slow forward or play pneumatic control 85 line is clear to operate through the valve 162 cutting off the opening 164.

Referring now to Figure 9, it will be noted that the valve consists of the tapered sleeve 90 162 having the opening 163 with which the tube 102, communicates, and an opposite opening 164. The sleeve also has an opening 165 which communicates with the tube 103, and an opposite opening 166 which is connected, by means of the tube 103, to the 95 valve chest 167, as shown in Figure 16. Within the tapered sleeve 162 is the core 168 having a pair of openings 169 and 170 therethrough. The core 168 is adapted to be rotated through the medium of the arm 100 171 by means of the pneumatics 172 and 173 (Figures 1 and 16). Upon the collapse of pneumatic 172, the valve member 168 is rotated in a clockwise direction, as seen in 105 Figure 16, and places the transverse opening 169 in a position to join the tube 102, to the opening 164, thus creating atmospheric pressure in the tube 102 and likewise in the tube 102. When atmospheric pressure is 110 admitted to tube 102, it operates a valve in the valve chest 167, which connects the tube 102, to the vacuum chamber in the valve chest 167, thus causing the operation 115 of the rewind pneumatic 66.

Upon the collapse of the pneumatic 173, the valve member 168 is rotated in a counter-clockwise direction, shutting off the tube 102, from the atmosphere, and connecting tube 103 to tube 102 through the opening 120 170.

The expression device shown at the left in Figure 16, and also in Figures 12, 13, 14 and 15, by means of which the volume of sound of the instrument is controlled will 125 next be described. This expression device consists of a pair of pneumatics 175 and 176 which are mounted on opposite sides of the fixed partition 177. Leading from the expression device is a tube 178 which communicates with the tube 179 extending to 130

- the main bellows or source of suction. Extending to the expression device is a tube 180 which communicates with the player action mechanism. The purpose of the expression device is to control the amount of air which passes from the tube 180 to the tube 178, and consequently the degree of vacuum or suction which is operative on the playing mechanism.
- 10 Extending downwardly from the lower edges of the movable sides of the pneumatics 175 and 176 are the arms 181 and 182 which are joined by the tension spring 183. As the spring 183 is maintained under tension, it constantly tends to keep the pneumatics 175 and 176 in expanded positions. If desired, the spring 183 may be made adjustable by providing a screw threaded extension 184 and an adjusting nut 185, as shown in Figure 16. The pneumatic 175 is provided for the purpose of determining the tension in the spring 183, and the pneumatic 176 is provided to regulate the flow of air from pipe or tube 180 to tube 178.
- 15 20 25 We will first describe the operation of the pneumatic 175. The tube 178 which is connected with the main bellows terminates in the expression device in an elongated recess 186, which communicates with the recess 187. Over the opening from the recess 187 is slidably mounted the valve plate 188, the position of which is adapted to be regulated through the medium of the rod 189 extending downwardly through the bottom of the pneumatic 175. In close sliding relation with the left surface of the valve plate 188 is a second valve plate 190 which is carried at one end of the flexible spring member 191, the opposite end of the spring 191 being rigidly secured to the movable side of the pneumatic 175 adjacent to the top thereof. The plates 188 and 190 are provided with the openings 192 and 193 which are adapted to be positioned so as to afford communication 30 35 40 45 from the recess 187 to the interior of the pneumatic 175 or to prevent the passage of air from the pneumatic 175 to the recess 187 and pipe 178.
- 50 55 60 65 As a partial vacuum exists in the chamber 187 at all times, when the instrument is in operation, it follows that if the plates 188 and 190 are so positioned that the openings 192 and 193 overlap, the suction will be communicated to the pneumatic 175 and tend to cause it to collapse, thus tensioning the spring 183. As previously stated, the plate 188 is adjustable through the medium of the rod 189 and in the operation of the device, the pneumatic 175 collapses only to the point where the plate 190 closes the opening 192 as the suction is then cut off from the pneumatic 175. The pneumatic 175 is provided with a very small bleeder opening 194 which is adjustable through the medium of screw 195. As the vacuum within the pneumatic

175 is relatively slowly reduced by the air passing through the opening 194, after a brief interval the pneumatic tends to open again, but as soon as the plate 190 uncovers a portion of the opening 192, the vacuum is re-established, thus again closing the pneumatic 175 to a position corresponding to the adjusted position of the plate 188. Thus the movable portion of the pneumatic 175 may, at times vibrate slightly back and forth, but at all times maintains a position substantially in accordance with the adjusted position of the plate 188.

The opening from the recess 186 to pneumatic 176 is adapted to be closed by the slideable valve plate 196 carried at the end of the flexible spring member 197, the opposite end of the spring 197 being securely fixed to the movable portion of the pneumatic 176 adjacent to the upper end thereof. The tube 180 which communicates with the player action terminates in the expression device in a laterally extending recess 198 which opens into the interior of the pneumatic 176. Thus the air which is drawn from the player action passes from the tube 180 into the expression device, thence into the elongated recess 186, and out through the tube 178 to the main bellows or source of vacuum. The partial vacuum, however, which is present in the pneumatic 176 tends to cause it to collapse, and through the medium of the spring arm 197 forces the valve plate 196 downwardly so as to partially close the slot leading to the recess 187. The collapse of the pneumatic 176 is at all times resisted by the tension in the spring 183, and the degree to which the pneumatic 176 will collapse, and consequently the degree to which the passage to the recess 186 is closed, will be governed by the degree to which the pneumatic 175 is collapsed.

If the amount of air being drawn from the player action was comparatively constant, the pneumatic 176 would remain substantially in a definite position, in accordance with the degree to which the pneumatic 175 was collapsed. However, the amount of air admitted by the openings in the player sheet varies constantly according to whether but a single series of notes is being played, or a number of series of notes are being played simultaneously. The present arrangement, however, provides that practically the same degree of vacuum will be maintained in the player action regardless of whether a small amount of air is being admitted through the music sheet openings, or a large amount. If the player is admitting a large amount of air, the vacuum existing in the pneumatic 176 will be slightly reduced, and under the influence of the spring 183, the pneumatic will expand, increasing the size of the opening in the recess 186. If, however, the amount of air admitted to the

player action is decreased, the vacuum within the pneumatic 176 will be slightly increased, causing it to collapse to a greater extent, thus moving the plate 196 downwardly to close a greater portion of the opening in the recess 186. In this way, the degree of vacuum in the player action is maintained at all times substantially constant, and in accordance with the position 10 occupied by the adjustable plate 188 of the pneumatic 175.

With the present expression device, any desired degree of volume between the two extreme limits may be obtained by adjusting 15 the plate 188 to the desired position.

While in the present disclosure, no particular means is disclosed for actuating the rod 189, it is to be understood that this rod may be adjusted by means of a lever extending 20 exteriorly to the instrument case, or, if desired, may be adjusted through the medium of openings in the music sheet strip.

The general operation of the device will now be described. We will first assume that 25 the controlling mechanism is in the position indicated in Figure 1, and it is desired to play a selection which is indicated by moving the pointer 133 to position 80. In setting the pointer, as just described, the shaft 30 will be rotated in a clockwise direction, as viewed from the right in Figure 16, and the disc 105 will also be rotated in a clockwise direction to place the extension 107 over the opening 97 which communicates 35 through tube 101 with the valve member in the valve chest 167 which permits the air to be exhausted from the fast forward pneumatic 67. Upon collapse of the pneumatic 67, the lower end of the shift bar 56 will be moved to the right, thus causing the gear 35 to be locked to shaft 30.

If now the motor is started into operation by the deposit of a coin, or in any other manner, the drum 63 will be rotated to rapidly wind the music strip. It will be recalled that the worm gear 81 always moves in unison with the forward wind drum 63, and at all times occupies a position in accordance with the amount of the music strip which is wound on the drum 63. Therefore, as the music strip is wound on the drum 63, the gear 81 will be rotated in a clockwise direction, thus bringing the notch 110 in the valve disc 105 into engagement 50 with the inwardly extending finger 109 carried by the selecting arm 108. Upon continued rotation of the gear 81, the movement of the outer edge of the disc 105 will be restrained by the finger 109, thus causing the disc 105 to rotate about its pivot pin 104 until the extension 107 occupies a position over the opening 98 in the face of the worm gear 81. At this time the roller 114 will enter the opening 124 in the gear 81, thus 55 locking the selecting arm 108 to the gear 81.

The tube 100 which terminates at one end in the opening 200 in the tracker bar 201 is now joined through the selecting mechanism to the tube 103. The cut-out valve 162 being at this time in a position to connect the tube 103 to tube 103₁, the connection is extended to the particular valve in the valve chest 167 which joins the tube 103, to the suction chamber. It is to be understood that there is provided in the music strip, preceding each of the selections thereon, a cutting 202 adapted to register with the opening 200 in the tracker bar 201. As the opening 200 is now uncovered by one of the cuttings 202 in the music sheet, the slow 75 forward or playing pneumatic 79 is collapsed, actuating the bar 74 which, through fingers 75 and 76, moves the shift bar 56 into its intermediate position. The gear 36 will now be locked to the shaft 30 while the gears 35 and 37 will be disconnected from the shafts 30 and 32 respectively, thus causing the music strip to be wound slowly upon the drum 63. When the selection has been 80 completely played, the motor will be shut off by appropriate means which need not be here described as it forms no part of the present invention.

Assuming now that it is desired to play a selection indicated by the position 13, the pointer 133 will be rotated in a counterclockwise direction, as viewed in Figure 1, until it occupies position 13. During this movement, the selecting disc 105 has been rotated in a counterclockwise direction, as viewed from the right in Figure 16, thus moving the extension 107 over the opening 99 which communicates through the tube 102 with the particular valve in the valve chest which joins the tube 102₁ to the exhaust chamber, thus causing the rewind pneumatic 66 to be collapsed. The collapse of the pneumatic 66 will shift the lower end of the bar 56 to the left, as seen in Figure 1, thus locking the gear 37 to the shaft 32 100 and causing the music strip to be rewound rapidly upon the drum 64.

As before, the worm gear 81 will move in unison with the music strip, but will travel in a direction opposite to that previously 115 described. During this movement, which will now be in a counterclockwise direction, as viewed from the right in Figure 16, the notch 110 will be brought into engagement with the finger 109, and disc 105 will be rotated to cause the extension 107 to overlie the opening 98. Now as the tracker bar opening 200 is uncovered by one of the cuttings 202 in the music strip, the playing pneumatic 79 will be collapsed, as previously 120 described, and the selected piece will be played.

When the music strip has been wound on the drum 63 so that all the cuttings on the last selection have passed beyond the tracker 130

bar 201, the opening 203 in the tracker bar will be uncovered by the rewind cutting 204 in the music strip which is placed following the end of the last selection. Opening 203 is joined through the tube 205 with the particular valve in the valve chest 167 which joins the tube 205₁ to the exhaust chamber. Thus, when the opening 203 is uncovered, the pneumatic 172 controlling the cut-out valve will be collapsed, rotating the movable member of the cut-out valve in a clockwise direction. In this movement, the valve 162 will connect the tube 102 to the atmosphere through the port 164, and will close the connection between tubes 103 and 103₁. As the tube 102₂ is now connected to the atmosphere through the tube 102₁ and port 164, the rewind pneumatic 66 will be collapsed and will cause the music strip to be rewound rapidly. When the strip has been completely rewound, the opening 206 in the tracker bar will be uncovered by the replay opening 207 at the beginning of the music strip, causing the pneumatic 173 to collapse and rotate the movable member in the valve 162 in a counterclockwise direction, thus closing the connection between tube 102 and port 164, and joining the tube 103 to tube 103₁. As the tracker bar opening 200 is at this time uncovered by one of the openings 202, the pneumatic 79 will be actuated to disconnect the gear 37 from shaft 32 and connect gear 36 to shaft 30. Thus, if it were not for the fact that the motor is stopped at this time by the means previously referred to, the first selection in the series would be played. If now a coin be inserted or the motor be tripped in any other manner, without the indicator having been moved, the first selection on the music strip will be played. Likewise, if the motor be tripped in any other manner, without the indicator having been moved, the first selection on the music strip will be played. Likewise, if another coin is inserted after the first selection has been played, without the indicator having been moved in the meantime, the second selection will be played, and so on. Thus, if the indicator is not moved, the instrument will continue to play the pieces successively, one after another, until all of the selections have been played, and will then return to the first piece, ready to repeat the operation.

At any time, however, when the instrument is at rest, the pointer 133 may be moved to a position to indicate any desired one of the selections on the music strip, and upon the subsequent operation of the instrument, the selected piece will be played. It should be noted that at all times while the instrument is in operation, the selecting arm 108 is locked to the worm gear 81 by reason of the roller 114 being positioned within the opening 124 in gear 81. It will be remem-

bered that the pneumatic 122, which forces the plunger 118 carrying roller 114 towards the gear wheel, is collapsed at all times while the main bellows is in operation. Thus during the playing of the successive pieces, the selecting arm 108 is carried around with the valve members, and its position in relation to the gear 81 can be changed only while the instrument is at rest.

As above explained, the controlling mechanism is moved by the shaft which carries the forward wind drum through the medium of the arm 86 and the slotted disc 84. This mechanism imparts a step by step movement to the selecting disc 105, thus insuring that when the slot or extension 107 of the controlling disc has reached a position such that it is about to overlie one of the control openings 97, 98 or 99 in the disc 81, the final movement will take place quickly, thus definitely determining the instant when the corresponding pneumatic will operate.

While in the drawings and in the above description but a single embodiment of applicant's invention has been disclosed, it is to be understood that modifications are contemplated and the invention should be limited, therefore, only by the scope of the appended claims.

What I claim as new and desire to secure by Letters Patent of the United States is:

1. In an automatic player piano, a pair of drums, means for rotating said drums in opposite directions to wind the music strip in one direction or the other, and a selecting device for controlling the operation of said drums, said selecting device consisting of a movable element operatively associated with one of said drums, a valve movably supported on said movable element and a co-operating movable element adapted to be manually set.

2. In an automatic player piano, a pair of drums, a motor mechanism, means for joining said motor mechanism to said drums for rotating them in opposite directions to wind the music strip in one direction or the other, and selecting means for controlling the operation of said means for joining, said selecting means consisting of a movable element operatively associated with one of said drums, a valve pivotally supported on said movable element and a co-operating element adapted to be manually set.

3. In an automatic player piano, a pair of drums adapted to receive the music strip, motor mechanism for rotating one or the other of said drums to move the strip in one direction or the other, means for selectively joining said drums to said motor mechanism, and a selecting device for controlling the operation of said means for joining, said selecting device consisting of two rotatable elements, one of which is operatively joined to one of said drums, the other being mount-

ed on said first rotatable element eccentrically of the latter's center of rotation so as to be carried thereby.

4. In an automatic player piano, a pair of drums adapted to receive the music strip, motor mechanism for selectively rotating one or the other of said drums to move the strip in one direction or the other, means for selectively joining said drums to said motor mechanism, and a selecting device for controlling the operation of said means for joining, said selecting device consisting of a rotatable element driven from one of said drums, an element carried by said rotatable

10 mechanism, and a third element movable independently of said first two elements and adapted to be set manually to actuate said second mentioned element.

5. In an automatic player piano, a pair of drums adapted to receive the music strip, motor mechanism for selectively rotating one or the other of said drums to move the strip in one direction or the other, means for selectively joining said drums to said motor mechanism, and a selecting device for controlling the operation of said means for joining, said selecting device consisting of a rotatable disc operatively joined to one of said drums and arranged to be driven thereby, said disc having perforations therein, a second disc rotatably mounted on said first disc and provided with a perforation, and an arm separate therefrom and adapted to be manually set and rotated step by step 30 incident to the operation of the piano, said arm being arranged to rotate said second disc to cause its perforation to overlie one or the other of the perforations in said first mentioned disc.

40 6. In an automatic player piano, a pair of drums adapted to receive the music strip, motor mechanism for selectively rotating one or the other of said drums to move the strip in one direction or the other, means for selectively joining said drums to said motor mechanism, and a selecting device for controlling the operation of said means for joining, said selecting device consisting of a rotatable disc operatively joined to one of said drums and arranged to be driven thereby, said drum having perforations therein, a second disc rotatably mounted on said first disc eccentrically of the latter's center rotation and provided with a perforation, and an arm adapted to be manually set and arranged to rotate said second disc to cause its perforation to overlie one or the other of the perforations in said first mentioned disc.

50 7. In an automatic player piano, a pair of drums adapted to receive the music strip, motor mechanism for selectively rotating one or the other of said drums to move the strip in one direction or the other, means for selectively joining said drums to said

motor mechanism, and a selecting device for controlling the operation of said means for joining, said selecting device consisting of a rotatable disc driven by one or the other of said drums, a second disc rotatably mounted on said first disc, said discs being provided with openings adapted to be brought into alignment upon rotation of said second disc on said first disc and an arm separate from said second disc adapted to be set manually and arranged to rotate said second disc in relation to said first disc when said first disc has rotated to a point corresponding to the set position of said arm.

8. In an automatic player piano, a pair of drums adapted to receive the music strip, a tracker bar motor mechanism for rotating one or the other of said drums to move the strip in one direction or the other, a pair of clutches for respectively joining said drums to said motor mechanism, a lever for operating said clutches, a pair of pneumatics for moving said lever in one direction or the other to selectively actuate said clutches, a second lever, means carried by said second lever for moving said first mentioned lever into neutral position, a pneumatic for actuating said second mentioned lever, and operating mechanism operable to selectively energize each of said three pneumatics through a single control aperture in said tracker bar.

9. In an automatic player piano, a pair of drums adapted to receive the music strip, motor mechanism for rotating one or the other of said drums to wind the strip in one direction or the other, clutches, one for each of said drums for joining it to the motor mechanism, a lever pivotally supported intermediate said clutches and provided with means for moving one or the other of said clutches into operative position as said lever is rotated in one direction or the other, a pair of pneumatics for selectively moving said lever, a second lever pivotally supported intermediate its ends, means projecting from said second lever adapted to engage said first lever on opposite sides of its pivotal support, a pneumatic for actuating said second lever, and a pair of spur gears adapted to operatively connect said motor mechanism with one of said drums upon the actuation of said latter pneumatic.

10. In an automatic player piano, the combination of a pair of drums adapted to receive the music strip, a driving member for selectively rotating one or the other of said drums, selective connecting mechanism for connecting said driving member to said drums for winding the strip in one direction or the other, a fast forward pneumatic for actuating said connecting mechanism to drive one of said drums for a fast forward motion of the music strip, a rewind pneumatic for actuating said connecting mecha-

nism to drive one of said drums for a rewind motion of said music strip, a playing pneumatic for actuating said connecting mechanism to drive one of said drums for a playing motion of said music strip, a primary valve for each of said pneumatics, selector mechanism comprising a control element adapted to be advanced with the motion of the music sheet, a tracker bar having a main control aperture therein, a main duct leading from said aperture to said selector mechanism, three ducts leading from said selector mechanism to the three primary valves which control said fast forward, rewind and playing pneumatics, said selector mechanism operating to place said main duct leading from the tracker bar control aperture in selective communication with said three ducts, separate valve means for preventing the operation of said playing pneumatic, venting means for venting atmosphere into the duct leading from said selector mechanism to the primary valve for said rewind pneumatic, and pneumatic means controlled from said tracker bar for controlling said separate valve means and said venting means.

11. In an automatic player piano, a pair of drums adapted to receive the music strip, 30 motor mechanism for selectively rotating one or the other of said drums to wind the strip in one direction or the other, means for selectively joining said drums to said motor mechanism, a selecting device for controlling the operation of said means for joining, said 35 selecting device consisting of two rotatable elements, one of which is operatively joined to one of said drums, the other being arranged to be set manually, a brake for preventing rotation of said manually set element, and means for applying said brake only when said piano is in playing operation.

12. In an automatic player piano, a pair 45 of drums adapted to receive the music strip, motor mechanism for selectively rotating one or the other of said drums to wind the strip in one direction or the other, means for selectively joining said drums to said motor mechanism, a selecting device for controlling the operation of said means for joining, said 50 selecting device consisting of one element arranged to be driven from one of said drums, and the second element adapted to be manually set, and a brake adapted to prevent movement of said manually set element, said brake being normally retracted to permit said manually set element to be moved freely, and pneumatically actuated means for applying said brake when said piano is in 55 normal playing operation.

13. In an automatic player piano, a pair 60 of drums adapted to receive the music strip, a driving member for selectively rotating one or the other of said drums to wind the

strip in one direction or the other, means for selectively joining said drums to said driving member and a selecting device for controlling the operation of said means for joining, said selecting device comprising a 70 plate having a plurality of concentric grooves in its face, a rotary member adapted to be advanced in substantial synchronism with the travel of the music strip, said rotary member having holes therein for 75 registration with said grooves, a valve member movably supported on said rotary member in direct contact therewith and having a passageway adapted to register with different ones of said holes, and a manually set 80 operating member adapted to move said valve in the rotation of said rotary member.

14. In an automatic player piano, a pair of drums adapted to receive the music strip, 85 motor mechanism for rotating one or the other of said drums to wind the strip in one direction or the other, means for selectively joining said drums to said motor mechanism, a selecting device for controlling the operation of said means for joining, said selecting 90 device consisting of two rotatable elements, one of said elements being arranged to be set manually, and driving means associated with one of said drums for moving the other 95 said element, said driving means consisting of an arm attached intermediate its ends to one of said drums, laterally projecting pins at the opposite ends of said arm, a shaft in geared relation to said driven element, a disc fixed to said shaft provided with a plurality 100 of radially extending slots, said pins being adapted to engage said slots on rotation of the corresponding drum.

15. In an automatic player piano, the combination of a pair of drums adapted to receive the music strip, a driving member for selectively rotating one or the other of said drums, selective connecting mechanism for connecting said driving member to said drums for winding the strip in one direction or the other, a fast forward pneumatic for actuating said connecting mechanism to drive one of said drums for a fast forward motion of the music strip, a rewind pneumatic for actuating said connecting mechanism to drive one of said drums for a rewind motion of said music strip, a playing pneumatic for actuating said connecting mechanism to drive one of said drums for a playing motion of said music strip, a primary valve for each of said pneumatics, selector mechanism comprising a control element adapted to be advanced with the motion of the music sheet, a tracker bar having a main control aperture therein, a main duct leading from said aperture to said selector mechanism, three ducts leading from said selector mechanism to the three primary valves which control said fast forward, rewind and playing pneumatics, said selector 125 130

- mechanism operating to place said main duct leading from the tracker bar control aperture in selective communication with said three ducts, cut-off valve means interposed in the duct leading from said selector mechanism to the primary valve for said playing pneumatic, venting means for venting atmosphere into the duct leading from said selector mechanism to the primary valve for said rewind pneumatic, a pair of control pneumatics for actuating said cut-off valve means and said venting means, primary valves for said latter controlling pneumatics, and ducts leading from said latter primary valves to apertures in said tracker bar.
16. In an automatic player piano, a pair of drums adapted to receive the music strip, motor mechanism for selectively rotating one or the other of said drums to wind the strip in one direction or the other, means for selectively joining said drums to said motor mechanism; a selecting device for controlling the operation of said means for joining, said selecting device consisting of an element operatively joined to one of said drums, and a second element adapted to be manually set relatively to said first element, said second element advancing with said first element when the latter is driven by said drum, and pneumatically actuated means for preventing relative movement between said elements while said piano is in playing operation.
17. In an automatic player piano, a selecting device consisting of an element adapted to be mechanically rotated, a second element arranged to be manually set, means for locking said second element to said first element, and pneumatic means for actuating said locking means.
18. In an automatic player piano, a pair of drums adapted to receive the music strip, motor mechanism, means for joining said motor mechanism to one of said drums rapidly to rewind the music strip, a second means for joining said motor mechanism to the other drum rapidly to wind said music strip, and a third means for joining said motor mechanism to said last mentioned drum to wind the said strip during playing operation, pneumatics for said means, respectively, for actuating the same, and selecting mechanism for controlling the operation of said pneumatics, said selecting mechanism consisting of a disc operatively associated with one of said drums and provided with openings, one for each of said pneumatics, a second disc rotatably mounted on said first disc and provided with an opening adapted to selectively overlie one or another of the openings in said first mentioned disc, and manually actuated means adapted to rotate said second mentioned disc to cause the opening therein selectively to overlie one or the other of the openings in said first mentioned disc.
19. In an automatic player piano, a pair of drums adapted to receive the music strip, a tracker bar, a driving member, means for joining said driving member to one of said drums to rewind the music strip, a rewind duct controlling said means, a second means for joining said driving member to the other drum to impart a fast forward motion thereto for winding said music strip, a fast forward duct controlling said second means, a third means for joining said driving member to one of said drums to slowly wind the strip during playing operation, a playing duct controlling said third means, an air venting aperture in the tracker bar for controlling said ducts, and valve mechanism operative to place said single controlling aperture in communication with either said rewind duct, said fast forward duct, or said playing duct.
20. In an automatic player piano, a pair of drums adapted to receive the music strip, a tracker bar, a driving member, means for joining said driving member to one of said drums to rewind the music strip, actuating means for said joining means comprising a pneumatic valve, a rewind duct controlling said pneumatic valve, a second joining means for joining said driving member to the other drum to impart a forward rotation thereto for winding said music strip, actuating means for said second joining means comprising a pneumatic valve, a forward motion duct controlling said pneumatic valve, a third joining means for joining said driving member to one of said drums to slowly wind the strip during playing operation, actuating means for said third joining means comprising a pneumatic valve, a playing duct controlling said pneumatic valve, a controlling aperture in said tracker bar, a selecting means comprising a movable element operatively associated with one of said drums and a cooperating moveable element adapted to be manually set, said selecting mechanism being operative to place said single control aperture of the tracker bar in communication with either said rewind duct, said forward motion duct, or said playing duct.
21. In an automatic player piano, a pair of drums adapted to receive the music strip, a tracker bar, a driving member for rotating one or the other of said drums, means for selectively joining said drums to said driving member to wind the music strip in one direction or the other, pneumatic means for actuating said joining means, selecting mechanism comprising a movable element operatively associated with one of said drums and a cooperating movable element adapted to be manually set, a duct between

- 5 said pneumatic means and said selecting mechanism, a valve cooperating with said duct for controlling the flow through the latter, a pair of pneumatics for operating said valve, and controlling apertures in said tracker bar for controlling said pneumatics.
- 10 22. In an automatic player piano, a pair of drums adapted to receive the music strip, a tracker bar, a driving member for rotating one or the other of said drums, means for selectively joining said drums to said driving member for winding said music strip in one direction or the other, pneumatic means for actuating said joining means, selecting mechanism comprising a movable element operatively associated with one of said drums and a cooperating movable element adapted to be manually set, a pair of ducts between said pneumatic means and said selecting mechanism, a rotary valve operable to vent one of said ducts to atmosphere and to cut off the other of said ducts, a pair of pneumatics for rotating said valve and a pair of control apertures in said tracker bar controlling said pneumatics.
- 15 23. In an automatic player piano, a pair of drums adapted to receive the music strip, a tracker bar, a driving member for selectively rotating one or the other of said drums to wind the strip in one direction or the other, means for selectively joining said drums to said driving member, a fast forward pneumatic for actuating said joining means to drive one of said drums for a fast forward motion of the music strip, a rewind pneumatic for actuating said joining means to drive one of said drums for a rewinding motion of said music strip, a playing pneumatic for actuating said joining means to
- 20 24. In an automatic player piano, a pair of drums adapted to receive the music strip, driving means for rotating one or the other of said drums to move the strip in one direction or the other, means for selectively joining said drums to said driving means, selector mechanism comprising a rotating element driven by one of said drums, a second movable element adapted to occupy definite positions relative to said rotating element, means for clutching said second movable element to said rotating element in one position, and pneumatic means governed by the operation of the piano for controlling said clutching means.
- 25 25. In an automatic player piano, a pair of drums, driving means, means for joining said driving means to said drums for rotating them in opposite directions to wind the music strip in one direction or the other, selector mechanism comprising a rotating element operatively associated with one of said drums, a manually set element adapted to cooperate therewith, means for clutching said manually set element to said rotatable element, and pneumatic means governed by the operation of the piano for controlling said clutching means.
- 30 26. In an automatic player piano, a pair of drums adapted to receive the music strip, driving means for rotating one or the other of said drums to wind the strip in one direction or the other, means for selectively joining said drums to said driving means, a selecting device for controlling the operation for said means for joining, said selecting device comprising two rotatable elements, one of said elements being arranged to be set manually, and driving means associated with one of said drums for moving the other said element, said driving means comprising a pair of Geneva gear elements for transmitting a step by step motion to the other said element.
- 35 In witness whereof, I hereunto subscribe my name this 15 day of June, 1923.
